[57] CLAIM

The ornamental design of a cover for a transport refrigeration unit, as shown and described.

DESCRIPTION

FIG. 1 is a perspective view of a cover for a transport refrigeration unit showing our new design;

FIG. 2 is an enlarged front elevational view thereof;

FIG. 3 is an enlarged top plan view thereof;

FIG. 4 is an enlarged bottom plan view thereof; and
FIG. 5 is an enlarged side elevational view thereof, the
opposite side being identical thereto.

FIG. 1

FIG. 2

FIG. 3

FIG. 4

FIG. 5
